UNITED STATES PATENT OFFICE.

CHARLES D. REYNOLDS, OF CRANSTON, RHODE ISLAND, ASSIGNOR, BY MESNE ASSIGNMENTS, TO THE NEW ENGLAND TRUST COMPANY, TRUSTEE, A CORPORATION OF MASSACHUSETTS.

WINDING MACHINE.

Application filed July 10, 1922. Serial No. 573,799.

To all whom it may concern:

Be it known that I, CHARLES D. REYNOLDS, a citizen of the United States, residing at Cranston, in the county of Providence, State 5 of Rhode Island, have invented certain new and useful Improvements in Winding Machines, of which the following is a specification.

This invention relates to improvements in 10 winding machines, and particularly to machines for winding heavy twine, cord, rope and the like.

One object of the improvement is to provide means for automatically placing the 15 supply-spool in a holder on the machine whereby it may be supported to rotate to deliver the material contained thereon to the winding-spindle.

Another object of the improvement is to 20 provide means for controlling the rotation of the supply-spool to regulate the unwinding of the material therefrom in accordance with the requirements of the winding operation.

Another object of the improvement is to 25 provide means for ejecting the empty supply-spool from its holder when the material on the spool has been exhausted and for replacing it with a full spool.

Further objects of the improvement are 30 set forth in the following specification which describes a preferred embodiment of the invention as illustrated in the accompanying drawings.

In the drawings:

Fig. 1 is a front view of a winding machine showing the present improvements applied thereto;

Fig. 2, a side view of the machine illustrating the supply-holder and its mechanism more in detail;

Fig. 3, a slightly reduced view of the supply-holder stand showing the means for ejecting the empty spool and applying the 45 full spool thereto and also the friction control for the spool; and

Figs. 4 and 5, detail views of the spool ejecting and replacing mechanism.

The machine in general comprises a box-like frame or head 2 mounted on suitable legs or standards 3 and provided with bearings for the rotatable winding-spindle 5 and cam-shaft 6. The winding-spindle 5 may

be driven by any suitable means, such as a belt (not herein shown) running over the usual "tight" and "loose" pulleys 7 and 8 and connected with the source of power. The winding-spindle 5 constitutes the drive-shaft of the machine and is connected to rotate the cam-shaft 6 by means of a train of gearing (not illustrated) enclosed within a casing 9 which is shown in Fig. 1. The cam-shaft 6 carries the usual helically-grooved cam 10 which engages with a roller or bowl 11 at the end of the reciprocable traverse-bar 12. The bar 12 is mounted to slide in horizontal grooves or guideways in a traverse-frame 13 and carries a forked thread-guide 15 at its outer end. Through this arrangement of mechanism the guide 15 is caused to be reciprocated longitudinally of the axis of the winding-spindle 5 so that the strand or cord leading through the fork in the guide is traversed back and forth to deposit it in helical coils which form the concentric layers of the cop or package. The traverse-frame 13 is pivoted on the cam-shaft 6 to adapt the traverse-guide 15 to swing away from the spindle 5 as the winding is built up thereon, and an arm 16, rising above the top of the frame, carries a pulley or sheave 17 over which the strand *c* leads to the fork in the guide. A second guiding-pulley or sheave 18 is mounted at the upper end of an arm or lever 19 pivoted on a bracket 20 which is supported on rods 21 extending rearwardly from the top of the machine frame 2. Attached to the lower end of the lever 19 is a spring 22 which is anchored to the frame 2 at 23. The spring 22 tends to maintain the lever 19 in erect position, as shown in Fig. 2, while allowing it to rock slightly to compensate for the fluctuation in resistance to the delivery of the strand *c* as it unwinds from the supply-spool S.

The spool S which carries the supply of material to be wound into the cop or package is supported to rotate under the control of a tension or unrolling-device arranged as later described. The supply-holder and its controlling-mechanism, together with the improved means for ejecting the exhausted spool therefrom and applying the full spool thereto form the subject-matter of the present invention and will now be described in detail.

Arranged at the rear of the legs 3 which support the winding-head 2 is a third leg or standard 4 having upright arms 25 connected to the ends of the horizontal rods 21 which support the bracket 20. The leg 4 is similar in construction to the rearward main leg 3, and formed on the inner sides of both legs 3 and 4 are inclined ledges or shelves 26 adapted to serve as opposite runways for the ends of a rod or shaft *s* which is inserted through the axial bore of the supply-spool S to serve as a mandrel therefor. As illustrated in Fig. 3, the ledges 26 reach out to the right of the standards 3 and 4, and inclining downwardly to the left, terminate at a point 27 on the opposite side of the standards. The ledges or shelves 26 are of substantially L-shape with vertical flanges 28 which act to guide the ends of the shaft or mandrel *s* as it rolls therealong. Overlying the ends 27 of the ledges 26 are hood-like guard-flanges 29 formed with curved portions 30 which serve as stops for the mandrel *s*, whereby the ends of the latter are guided into the two opposite sockets 31 carried by a pair of pivoted sector-arms or levers 32. The arms 32 are provided with axial studs 33 which are journaled in hub-like bearings 34 on the sides of the legs 3 and 4, see Fig. 5. Fast on the outer ends of the studs 33 are collars 35 formed with crank-arms 36, to which are jointed a pair of links or rods 37, see Fig. 1. The outer ends of the links or rods 37 rest on ledges 38 on the sides of the standards 3 and 4, and are bent into hooks 39, see Fig. 2, which are adapted to be engaged by upright fingers 41 on a rockable frame 40 to be later described. The arms or levers 32 which carry the sockets 31 for the ends of the spool-mandrel *s* are caused to be rocked for a two-fold purpose; first, to release the mandrel *s* of the empty spool S from the socket-arms; and secondly, to effect the tripping of a detent-mechanism which allows a full spool to be automatically delivered to the supply-holder. Referring to Fig. 3, it has already been explained that the axial rod or mandrel *s* in the spool S is supported on the inclined ledges 26 to adapt it to roll downwardly to seat itself in the bearing-sockets 31 of the arms 32. To prevent the new spool from rolling against a spool already supported from the socket-arms 32 a 55 detent or stop-device is provided in the form of two opposite trip-levers 45. As shown most clearly in Figs. 3 and 4, the trip-levers 45 are of elbow shape, being pivoted at their rearward ends on studs 46 projecting from the webs or ribs of the ledges 26. Projecting downwardly from the apex of the levers 45, across the top of the flanges 28, are the stop-lugs or detents 48 which are adapted to rest against the top of the ledges 26, as shown in Fig. 3, to engage

the ends of the mandrel *s* as it rolls therealong. The forward ends of the levers 45 are provided with cross-pieces or shoes 49 adapted to be engaged by the rounded ends of curved projections or fingers 50 on the socket-arms 32. As shown in Fig. 3, the fingers 50 are of arcuate shape and project laterally from the sides of the arms 32 through curved slits or openings 51 in the webs of the standards 3 and 4, whereby to bring them into position to engage the shoes 49 on the levers 45 which are arranged on the outside of the standards. When the arms 32 are rocked into position to eject the empty spool mandrel *s* from the sockets 31, as shown in Fig. 4, the fingers 50 will be raised against the shoes 49 to lift the trip-levers 45 to release their detents 48 from the ends of the mandrel *s* of the full spool S. The return movement of the arms 32 is limited by the engagement of the fingers 50 with the ends of the slits 51, whereby the arms will be maintained normally in the position shown in Fig. 3 with their sockets 31 ready to receive the ends of the mandrel *s* as it rolls off from the ends of the ledges 26.

Below the socketed ends of the arms 32 the guard-flanges 29 are continued in curved runways 54 which are extended to the right in the inclined ledges 55 reaching out beyond the sides of the standards 3 and 4 and terminating in stop-ledges 56. Arranged concentrically with the curved runways 54 are guard-flanges 57 which serve to direct the ends of the empty spool mandrel *s* downwardly to cause the latter to roll out to the end of the ledges 55 where the spool may be conveniently removed from the machine.

Projecting from the left-hand side of the legs 3 and 4 are arms 58 provided with hubs 59 for supporting a horizontal rod or shaft 60 on which the rockable frame 40, before referred to, is pivoted. Referring to Fig. 2, the frame 40 is constructed with two vertical side arms 61 having hubs at their lower ends journaled on the ends of the shaft 60, and a central arm 62 having its hub journaled on the shaft between the fixed collars 63. The arms 61 and 62 are connected at the top by a horizontal cross-strut 64, at the ends of which are the upright fingers 41 which engage with the hooked ends of the rods 37 to rock the socket-arms 32. Connected to lugs 66 on the sides of the frame 40 are cords or straps 67 which lead back over pulleys or sheaves 68, shown in Fig. 1, journaled on the sides of the legs or standards 3 and 4. Suspended from the ends of the cords 67 are suitable holders 69 carrying weights 70 which act to maintain the frame 40 in vertical position resting against stop-bosses 71 on the curved runways 54 which project at the side of the

legs 3 and 4. In addition to the force exerted by the weights 70 there is also an added pressure applied to the frame 40 by means of a pair of springs 72. The 5 springs 72 are fastened to hooks 73 on the sides of the frame 40 and anchored to arms 74 projecting from brackets attached to the legs 3 and 4, see Fig. 1.

The central arm 62 of the frame 40 is 10 continued downwardly from its hub in a foot-lever 75 provided with a rest or treadle 76 at its lower end. Attached to the side of the foot-lever 75 are counterweights 77 held on a cross-rod 78. The foot-lever 75 15 is thus caused to act as a weighted pendulum to steady the movement of the frame 40. Attached to the side of the central arm 62 beneath the cross-strut 64 is a hand-lever 80, see Fig. 2, reaching upwardly with its 20 handle at a convenient height to be grasped by the operator as he stands with his foot on the treadle 76.

The frame 40, besides serving to effect the rocking movement of the socket-arms 25 32, also has a further, prime function in applying frictional pressure to the supply-spool S to control its rotation to regulate the unwinding of the strand of material therefrom. Referring to Figs. 2 and 3, at 30 the center of the cross-strut 64 is an upright arm 83 carrying a hub 84 to which is pivoted a pressure-member 85. The pressure-member or friction-brake 85 consists in a substantially V-shaped shoe having 35 relatively broad, convex faces 86 adapted to bear against the surface of the cylindrical body of material wound on the spool S. The flaring, convex faces of the shoe 85 provide for an extended two-point bearing between the shoe and the spool whether the body of the latter be at the maximum or minimum diameter.

Having now described the construction and arrangement of the mechanism of my 45 improved machine, its method of operation will next be explained: Assuming that an exhausted spool S is held on its mandrel s in the sockets 31 of the arms 32, and that a full spool S has been placed in reserve position with its mandrel s resting on the ledges 50 26 of the runway between the standards 3 and 4, being held by the stops 48 on the trip-levers 45 as shown in Fig. 3, the operator proceeds as follows to eject the empty 55 spool and replace it with the full one: By placing the foot on the treadle 76 and grasping the hand-lever 80 the frame 40 may be easily rocked back against the force of the weights 70 and springs 72. The brake-shoe 85 will thus be withdrawn from contact 60 with the barrel of the empty spool S, and as the frame 40 moves back still farther the fingers 41 at its sides will eventually come into engagement with the hooks 39 on the 65 ends of the links or rods 37 connected to

the crank-arms 36. Immediately this engagement takes place the continued movement of the frame 40 will cause the links 37 to be drawn forward on their ledges 38 to rock the crank-arms 36 to turn the pivot-studs 33 of the socket-arms 32. This action causes the arms 32 to be rocked or tilted upwardly into the position illustrated in Fig. 4, whereby their sockets 31 will be turned over to release the ends of the mandrel s of the empty spool S. The empty spool will thus be ejected from the holder and the force of gravity will cause it to drop with its mandrel sliding in the curved runway formed by the ledges 54 and guard-flanges 57. The ends of the mandrel s are guided onto the inclined ledges 55, and rolling therealong, will finally bring up against the stops or abutments 56 where the spool is held in convenient position to be lifted 70 out and removed from the machine.

Meanwhile, as the ends of the socket-arms 32 are rocked upwardly, their curved fingers 50 will come into contact with the shoes 49 on the trip-levers 45, and riding thereagainst will lift said levers to release their detents 48 from the ends of the mandrel s carrying the reserve supply-spool S. The full spool S is thus allowed to roll down the runway and if the arms 32 are not immediately returned to first position the ends of the mandrel s in the spool will be caught by the lips of the sockets 31 after it rolls off from the ledges 26. Now as the operator releases the pressure on the treadle 76 and allows the frame 40 to swing back into operative position, under control of the hand-lever 80, the weight of the arms 32 will cause them to be returned into position to receive the ends of the reserve spool mandrel s in their sockets 31. As the full spool S is thus delivered into place, with its mandrel s supported from the arms 32, the brake-shoe 85 carried by the frame 40 will be brought into engagement with the surface of the windings on the spool.

With the full spool S held in the supply-holder in the manner as above described its material is delivered to the winding-spindle 5 as next explained: The strand or cord c is drawn off from the side of the spool S away from the brake-shoe 85, led up over the sheave or pulley 18 on the compensating-lever 19, thence around the sheave 17, through the fork in the traverse-guide 15 and its end attached to the winding-spindle 5. The operator now starts the operation of the machine by shifting the belt from the "loose" to the "tight" pulley, or by manipulation of any other suitable control mechanism, and the winding proceeds as follows: As the winding-spindle 5 is rotated it winds the strand c thereon while the latter is traversed back and forth by means of the 115 guide 15 which is reciprocated from the cam 120 125 130.

10. The cop or package is thus caused to be built up in superimposed layers of helical coils with its supply delivering thereto from the spool S held by the socketed arms 32. 5 As the material is drawn off from the supply-spool S the rotation of the latter is checked and controlled by the action of the pressure-member or brake-shoe 85 which is maintained constantly bearing against the 10 body of the spool under the action of the frame 40 moved by the weights 70 and springs 72. The delivery of the material is thus regulated to apply sufficient resistance to the draft on the strand c to provide 15 the necessary tension whereby the winding will be built up in a firm, compact package. Any undue resistance or hindrance to delivery of the strand at the supply-spool is compensated for by the yielding action of the arm 19 carrying the guiding-pulley 18, and in this way the material feeds to the winding spindle with a practically constant tension.

When the material on the supply-spool is exhausted the winding operation is arrested under the action of automatic stopping-devices controlled from the compensating-lever 19. These latter devices are not herein shown or described in detail, 30 however, as they do not relate particularly to the present invention. While the machine is in operation the operator places one or more reserve supply-spoils on the runways 26 at the top of the standards 3 35 and 4. When, therefore, the material on the delivering spool runs out and the machine stops, it is only required to draw back the frame 40 to eject the exhausted spool and cause a full spool to be substituted in the manner as first explained. With the 40 fresh spool in place it is only necessary to tie up the ends and start the machine again.

It will be observed from the foregoing that the improvement provides for furnishing a practically continuous supply of material to the winding-machine without the long intervals of stoppage usually required for doffing the empty spools and replacing them with full ones. That is to say, the doffing and replacing of the spools may be accomplished much more rapidly and conveniently than heretofore, and hence the ultimate production of the machine is materially increased. In addition, the device embodies an improved controller for regulating the delivery of the material to apply the required tension on the strand, which is operated by the same means that controls the doffing and replacing of the supply-spool.

While I have herein shown and described one preferred embodiment of the improvement it is to be understood that various modifications may be made in the form and construction of the apparatus without de-

parting from the spirit or scope of the invention; therefore, without limiting myself in this respect, I claim:

1. In a device of the type specified, the combination of a supply-holder for supporting a supply-spool to adapt it to deliver its material, means to actuate the supply-holder to doff an exhausted spool therefrom, and means operated thereby to feed a fresh spool to position on the supply-holder. 75

2. In a device of the type specified, the combination of displaceable means for holding a supply-spool to adapt it to deliver its material, means for displacing said holding-means to doff an exhausted spool therefrom, and means operated by the displacement of the holding-means to apply a fresh spool to delivery position thereon. 80

3. In a device of the type specified, the combination of a movable supply-holder for supporting a spool to adapt it to deliver its material, means for moving the supply-holder to eject an exhausted spool therefrom, and means operated upon the return of the supply-holder to first position to supply a fresh spool thereto. 85

4. In a device of the type specified, the combination of a movable supply-holder for supporting a spool to adapt it to deliver its material, means for supporting reserve spools adjacent the supply-holder, means to move the supply-holder to eject an exhausted spool therefrom, and means operated from the movement of the supply-holder to release a reserve spool to cause it to feed into the supply-holder. 90

5. In a device of the type specified, the combination of a movable supply-holder for supporting a spool to adapt it to deliver its material, a runway for supporting a reserve spool in position to be fed to the supply-holder, means operated by the movement of the supply-holder to eject an exhausted spool therefrom, and means rendered operative upon the movement of the supply-holder to cause the reserve spool to be fed from the runway thereto. 105

6. In a device of the type specified, the combination of a displaceable supply-holder for holding a spool to adapt it to deliver its material, a runway for holding a reserve spool to adapt it to feed into position in the supply-holder, a runway for receiving the empty spool ejected from the supply-holder, means to displace the supply-holder to eject the empty spool into one runway, and means operated therefrom to cause the reserve spool to feed from the other runway into the supply-holder. 115

7. In a winding machine, the combination of a supply-holder for supporting a spool in position to deliver its material to the machine, means for supporting a reserve spool in position to feed into the supply-holder, detent-means for holding the reserve spool 120

from feeding, and means to eject the empty spool from the supply-holder and release the detent-means to allow the reserve spool to feed thereto.

5 8. In a winding machine, the combination of a supply-holder for supporting a spool to adapt it to deliver its material to the machine, a runway leading to the supply-holder, detent-means for holding a reserve spool on

10 the runway, a second runway leading from the supply-holder, and means to eject the empty spool from the supply-holder into the second runway and to release the detent-means to permit the reserve spool to feed

15 from the first runway into the holder.

9. In a winding machine, the combination of a rockable supply-holder for supporting a spool to adapt it to deliver its material to the machine, means for holding a reserve

20 spool adjacent the supply-holder, means for rocking the supply-holder to eject an empty spool therefrom, and means operated thereby to release the reserve spool to adapt it to seat itself in the supply-holder.

25 10. In a winding machine, the combination of rockable arms for holding a supply-spool to adapt it to deliver its material to the machine, means to rock said arms to cause an empty spool to be ejected there-

30 from, means for holding a reserve spool in position to feed into place in the arms, and means operated from the rocking action of the arms to release the reserve spool from its holding-means.

35 11. In a winding machine, the combination of a pair of pivoted arms having sockets for receiving the mandrel of a supply-spool, a runway arranged above the arms to adapt a reserve spool to feed therewith, and

40 trip-levers for holding the reserve spool from feeding, and means for rocking the arms to eject an empty spool therefrom and to release the trip-levers to allow the reserve spool to feed into place on the arms.

45 12. In a winding machine, the combination of a pair of rockable arms having means for supporting a supply-spool to adapt it to deliver its material to the machine, a runway for supporting reserve

50 spools in position to feed into position on the arms, trip-levers for holding the reserve spool from feeding to the arms, and manually-operated means for rocking the arms to eject the empty spool therefrom and to re-

55 lease the trip-levers to permit the reserve spool to feed thereto.

13. In a winding machine, the combination of a rockable supply-holder for supporting a supply-spool to adapt it to deliver

its material to the machine, an inclined runway leading to the supply-holder, a second inclined runway leading from the supply-holder, trip-levers for holding a reserve spool from feeding along the runway and arranged to be operated from the rocking-action of the supply-holder to release the spool, and manually-operable means for rocking the supply-holder.

14. In a winding machine, the combination of a supply-holder for supporting a spool to adapt it to rotate to deliver its material to the machine, pressure-means for controlling the rotation of the spool in unwinding the material therefrom, means to withdraw the pressure-means from the spool, and means operated therefrom to eject the exhausted spool from the holder to permit its replacement with a full spool.

15. In a winding machine, the combination of a supply-holder for supporting a spool to adapt it to rotate to deliver its material to the machine, pressure-means for controlling the rotation of the spool in unwinding the material therefrom, means for ejecting an exhausted spool from the holder and replacing it with a full spool, means for withdrawing the pressure-means from the spool, and means operated therefrom to cause the action of the spool-ejecting and replacing means.

16. In a winding machine, the combination of a supply-holder for supporting a spool to adapt it to deliver its material to the machine, mechanism for ejecting an exhausted spool from the holder and replacing it with a full spool, braking-means acting on the spool to control its rotation in unwinding the material therefrom, means for applying pressure to the braking-means, means to withdraw the braking-means from the spool, and means actuated from the withdrawal of the braking-means to operate the spool-ejecting and replacing mechanism.

17. In a winding machine, the combination of a supply-holder for supporting a spool to adapt it to deliver its material to the machine, mechanism for ejecting an empty spool from the supply-holder, a rockable frame, means carried by said frame to apply a braking-pressure to the spool to control its rotation, means to rock said frame to release the braking-means, and means actuated from the frame after the release of the braking-means to operate the spool-ejecting means.

In testimony whereof I affix my signature.

CHARLES D. REYNOLDS.
